UNITED STATES PATENT OFFICE

2,627,374

GAME SCORING DEVICE AND ASH TRAY

Raymond G. Mulder, Chicago, Ill.

Application April 6, 1950, Serial No. 154,385

3 Claims. (Cl. 235—118)

1

This invention relates to a new and improved type of an ash tray particularly adapted for card players. More specifically it is directed to an ash tray having in combination therewith an information containing means which will constantly remind all players impartially throughout the entire game of all facts pertaining to the particular game under way.

In playing card games as a pastime or even as an avocation, the successful bidder selects a trump which in his estimation will be most useful in obtaining the number of tricks or points for which he is obligated. In course of the game, particularly if it is a very close and exciting contest, one or more of the participants may forget the number of tricks bid or points to be accumulated and upon completion of the game, oftentimes challenges the bidder in this respect. Such challenge not only causes a loss of time used in settling the disputed question but also occasionally leads to altercations and even fisticuffs among the players.

Even if the game shall be very friendly such as is commonly referred to as a "social" game of cards, the lapse of memory occurs particularly if the spell of interjected social conversation may be of unusual interest. Then all participants including the successful bidder will look blankly at each other in hapless confusion and bewilderment to determine what is the trump or what is the amount played.

Such moments of forgetfulness on the part of one or more players are very likely to occur on more than one occasion during an evening's play of cards. They are embarrassing not only to the players but also particularly to the successful bidder who should at all times be alert mentally during the progress of a game.

It, therefore, is an object of my invention to provide a useful article of manufacture that will constantly remind all participants in the game of the exact nature of the trump card and the amount of tricks or points to be scored during the game.

A further object of my invention is to provide an article of manufacture that will facilitate card playing and assist the participants thereof in settling amicably any disputes.

A still further object of my invention is to provide an article of manufacture that will not only constantly remind participants of a card game but also function as a useful collecting device for ashes and other table debris normally accumulated during card games.

A still further object of my invention is to

2

provide an article of manufacture which is not only utilitarian but also aesthetically desirable on or about a card table top.

These and other objects, adaptations, variations, extensions and modifications will become readily apparent to one skilled in this art particularly in light of the clear, lucid and accurate description given hereinbelow of the principles underlying my invention and the application 5 of such principles as incorporated in a specific embodiment of the preferred form or type of my invention which are further clearly illustrated in the annexed drawing forming a part of this disclosure in which:

15 Figure 1 is a plan view of the preferred embodiment of my invention.

Figure 2 is an elevational view of the same.

Figure 3 is a vertical section taken in the direction of the arrows through the lines 3—3 of 20 Figure 2.

Figure 4 is a bottom plan view of a section along line 4—4 of the portion of the edge of the device of Figure 3.

Figure 5 is a segment of the device showing in 25 perspective the trump indicator wheel, while

Figure 6 is a perspective of the indicator wheel.

For sake of clarity and definitiveness, the elements in my invention as disclosed in the drawings, will be identified with characters which 30 will be used in identically the same office hereinafter to refer to the same in the drawing.

My improved device is a base 10 preferably substantially annular in shape and having a beveled edge 12. In the central portion of said base 10 is an annular opening 14 which has formed therein female threads 16 which engage the male threads 18 formed on the annular projection 22 of the cup 20. The annular projection 22 fits snugly within the opening 14 and 35 is threaded engaged by means of the threads 16 and 18 to form a fixed unit, or threads may be omitted and parts pressed together.

The cup 20 has an extending peripheral lip 24 which forms a retaining collar 26 to retain

40 between it and the upper surface 11 of the base 10 an annular ring 30, whose outer edge is substantially a curved beveled surface 28. Spaced about the periphery or curved beveled surface 23 of the ring 30, are a series of depressions 32 45 separated from each other by means of projecting ridges or dividers 34 to form therebetween an indicia receiving surface. Various indicia like 66, 70, 75, etc. as indicated in the drawings, or others depending on the nature of the card 50 game that is being played, can be adhesively or

otherwise attached, embossed, etc. within the depressions 32. Clearly, the configuration of the said indicia receiving surfaces 32 can be varied considerably and still be within the spirit of the fundamental concepts underlying my invention. For instance, they may be circular, oval, etc. instead of rectangular as shown in the preferred embodiment. Likewise, these may be raised above the surface in cameo-like fashion and the dividers 34 may be depressed instead of being elevated as shown in the preferred embodiment. It is self evident that one skilled in the art may vary this element quite freely and still be within the spirit of the entire invention.

It should be noted that the ring 30 is to revolve about the cup 20 as a shaft. As it revolves, any of the indicia marking spaces 32 can be stopped selectively over a window 36 cut into the base 12. This window 36 is shown as being substantially rectangular in shape though clearly it can be varied widely by one skilled in the art.

This window 36 provides access to an indicia carrying wheel 38 mounted within the recess 40 located along the edge of the base 12. A screw 42 of a special wide flange head type is fitted into the base 12 to hold in place the wheel 38 which revolves freely about the projection 44 of the base 12.

As the wheel 38 has spaced equidistantly apart along its edge 46 a number of desired indicia 48 to indicate the character of the trump in the card game, while the indicia like 66, 70, 75, etc. on the ring 30, show the amount played.

In use, the dealer sets the number of points to be obtained on play over the window 36 and 35 then adjusts the trump indicator wheel 38 to show the proper indicia 48 in the window 36. During the course of play or upon its conclusion, every player including the kibitzing onlookers knows exactly what the trump is and what points are 40 needed to win the game.

To render the article more utilitarian, I provide a large capacity recess 50 to receive therein ashes, stubs, matches, etc. A series of notches 52 are also provided to prevent cigars and cigarettes from falling off the rim 24.

It is clearly apparent that the various elements of the fundamental concepts underlying

my invention can be varied widely by one skilled in the art and still be within the ambit of the spirit of my invention as defined by the hereunto appended claims.

5 I claim:

1. A game scoring device comprising a base, a shaft mounted thereon, means to mount said shaft on said base, an annular ring mounted on said shaft, a means on said shaft to retain said annular ring in juxtaposition between said base and about said shaft, game indicia spaced about the periphery of said ring, a recess within a section of the edge of said base, an indicia bearing wheel mounted within said recess and a means to retain said wheel in juxtaposition within said recess, whereby a portion of said wheel will be visible through opening of said recess.

20 2. In the article of claim 1, wherein said annular ring is free to revolve about said shaft, a lateral collar extending beyond and over the upper edge of said shaft to restrain upward displacement of said annular ring.

25 3. In the product of claim 1, wherein the said annular ring has surface depressions about its periphery, and the said game indicia disposed about in said depressions.

RAYMOND G. MULDER.
